ROLLER ADJUSTMENT FOR PRESSES

William Gegenheimer, Brooklyn, N. Y., assignor
to Willard Manufacturing Corporation, New
York, N. Y., a corporation of New York

Application August 26, 1936, Serial No. 98,090

5 Claims. (Cl. 308—59)

This invention is an adjustment means for bearings, and while it is susceptible of general use where the adjustment of certain types of bearings is required, it is adapted particularly for use in connection with printing or lithograph presses.

An important object of the invention is to provide means of simple construction for accurately and minutely adjusting the bearing spindle of a roller or shaft and locking the bearing securely in such adjusted position.

A further object of the invention is to provide means for carrying out the adjusting and locking operations without the necessity of stopping the 10 operation of the machine and form a position convenient to an operator.

With these objects in view, together with others which will appear as the description proceeds, the invention consists in the novel construction, combination and arrangement of parts, all as will be described more fully hereinafter, illustrated in the drawing, and particularly pointed out in the 20 claims.

In the drawing:

Figure 1 is a front elevation of one end of a conventional form of roller for printing or lithograph presses and illustrating in section the bearing adjustment device of my invention,

Figure 2 is an end elevation of the roller and 30 adjustment device,

Figure 3 is a view similar to Figure 1 and showing the position the parts may assume in making an adjustment, and

Figure 4 is a transverse sectional view taken 35 substantially upon line 4—4 of Figure 2.

Referring now more particularly to the drawing 5 represents the journal or supporting end of a roller 6, its contacting or cooperating roller or cylinder being indicated at 7. The frame of the 40 press is represented generally at 8, and is of conventional or well known form.

Associated with the frame 8 is a block or support 9, recessed or channeled in one side as at 10 to receive a projection 11 on the frame. A bolt 12 45 is threaded laterally through the frame 8, passes through the projection 11 and threadedly engages in the block or support 9. Operation of this bolt is carried out by means of the head 13, and it is apparent that rotation of the bolt will cause the 50 block to move upon the projection 11 depending upon the direction of rotation of the bolt.

The block or support 9 is provided with an opening or passage 14 disposed at right angles to the axis of the bolt 12, and in which is slidably mounted a standard 15 carrying a bearing 55

sleeve or yoke 16 at its upper end. This yoke supports the journal 5 of the roller.

The means for adjusting this standard longitudinally within its opening or recess includes a threaded pin or screw 17 passing through a suitable internally threaded opening in the base of the block and parallel to the bolt 12. The opening for this screw or pin communicates with the recess or opening 14 near the lower end thereof, and the inner end of the pin or screw is beveled, 16 tapered or inclined as indicated at 18. This tapered end engages beneath and supports the standard 15, and it is at once obvious that reciprocation of the pin within its opening will cause the standard 15 to move upwardly or downwardly 15 depending upon the direction of axial travel of the pin. The lower end of the standard 15 is bored as shown to receive a screw 19 whose head 20 is beveled as shown for contact with the inclined end of the screw or pin 17. 20

Associated with the adjusting screw 17 are means for locking the said screw in adjusted position. This means includes a plug 20' slidable in a passage or opening 21 disposed laterally of the block and entering one side of the passage for 25 the screw 17. An internally threaded opening 22 is arranged in the block 9 at right angles to the passage 21 and parallel to the opening for screw 17. This passage 22 receives a locking screw 23 whose inner end is tapered as at 24 for 30 engagement behind the plug 20'.

It will be observed that the outer ends of screws 17 and 23 are disposed relatively close to one another and are socketed to receive an adjusting or operating tool. By so arranging these 35 screws it is obvious that they may be operated without stopping the machine so that adjustments may be made while the latter is in operation. It is also obvious that the operative ends of these screws are readily accessible for manipulation. 40

While but one end of the journal or shaft is shown in the present illustration, it will be understood that the mechanism here described will be duplicated at the opposite end of the shaft. When 45 it becomes necessary to adjust the shaft, in order that the roller may be moved toward or away from its cooperating cylinder as desired, this adjustment may be readily made by rotating screw 17 with a proper tool in such direction as will 50 cause the standard to rise or fall as desired. The particular arrangement is such that a most minute adjustment may be made, thus satisfying the high degree of accuracy required in press operations. 55 Rotation of pin or screw 17 in clockwise direc-

tion will cause the beveled or tapered end thereof to project further into the opening 14, whereupon this movement is transmitted to the standard 15 by engagement of the tapered end 18 with the beveled end of screw 20. When the desired adjustment has been made, rotation by a suitable tool of screw 23 causes the beveled end thereof to engage behind plug 20' and force the same into engagement with the side of screw 17, thus holding the latter securely against rotation in either direction. The range of adjustment of standard 15 may be increased or diminished by adjustment of the screw 19 in the lower end of the standard. The ends of the plug 20' may be beveled as shown in Figure 4 to insure proper cooperation between the plug and the locking screw 23 and also to insure proper locking engagement between the plug and the screw 17.

From the foregoing, it is apparent that adjustment of the shaft 5, either axially or radially may be quickly and easily made. Rotation of bolt 12 in the proper direction will cause the plug and its shaft supporting yoke to move in such direction as will secure axial adjustment of the roller, while operations of the screw or pin 17 secures the proper vertical adjustment of the shaft. By arranging the adjusting screw and the lock therefor in the manner shown and described, ready access for these adjustments may be had from the side 30 of the machine and without necessitating stopping or slowing down of the machine during such operations.

What I claim is:

1. In a bearing adjuster, a block, a bearing standard slidable in said block, a screw in said block, the inner end of said screw tapered and engageable with a surface of said standard, whereby movement of the screw will be transmitted to said standard, a locking plug in said block adapted to engage a side of said screw, and a locking screw in said block parallel with said first mentioned screw, said locking screw having an inclined inner end to engage and move said plug.

2. In a bearing adjuster, a frame, a block, a

bolt in said frame engaged in said block, said block having an opening therein, a standard slidable in said opening, a screw in said block having a tapered inner end, said end projecting into said opening and in engagement with the lower end of said standard, said block having a passage communicating with one side of said screw, a locking screw in said block in spaced parallel relation with said first mentioned screw and having a tapered inner end, a plug slidable in said passage, the tapered end of said locking screw engaged behind said plug, whereby movement of said locking screw in one direction will move said plug into engagement with said first named screw.

3. In a bearing adjuster, a block having an opening, a bearing standard in said opening, a screw disposed axially in the lower end of said standard, a beveled head on said screw, said block having a lateral opening disposed at substantially right angles to said standard and communicating with the lower end of the opening therefor, and the inner end of said screw being tapered and engaged with the beveled head on said first named screw.

4. In a bearing adjuster, a support, a bearing slidable in said support, an adjusting screw in said support for moving said bearing, a locking plug in said support for engagement with said adjusting screw, and a locking screw in said support in spaced parallel relation to said adjusting screw for moving said plug into engagement with said adjusting screw.

5. In a bearing adjuster, a bearing support, a standard slidable longitudinally in said support, a bearing on said standard, an adjusting member in said support disposed parallel with said bearing and adapted to move said standard, a locking plug in said support adapted to engage and lock said adjusting member, and an operating element in said support disposed parallel with said adjusting member for moving said plug.

WILLIAM GEGENHEIMER.
